4 Claims. (Cl. 315—336)

1

This invention relates to devices comprising an electric discharge tube having a liquid cathode and at least two capacitive ignition electrodes.

In discharge tubes of known type having a liquid cathode and more than one capacitive ignition electrode, the ignition electrodes are, as a rule, connected in parallel. Since the ignition electrodes can be made identical only with difficulty, the position is usually such that one of the ignition electrodes only is operative until it becomes defective, whereupon it is switched off by means of a fuse. The total life of the tube is in this case not longer than the sum of the lives of the ignition electrodes so used.

For many uses and more particularly for devices intended for high-frequency heating, the short lives of tubes having a capacitive ignition electrode is a serious inconvenience, more particularly because other types of tubes suitable for this purpose have short lives or unsatisfactory outputs.

The object of the invention is to mitigate the said disadvantages.

According to the invention, a device comprising an electric discharge tube having a liquid cathode and at least two capacitive ignition electrodes, is characterized in that the ignition electrodes are used in such manner that two sequential ignitions are not performed by one ignition electrode.

The life of the discharge tube for the same load is thus made longer than would be expected from the number of ignition electrodes. This may be attributable to the fact that the amount of heat developed by the ignition pulse and due to the vicinity of the arc produced is divided over a plurality of ignition electrodes, so that the mean temperature of the ignition electrodes is lower than if only one ignition electrode were used in the tube with the same load. Consequently, it is desirable that the ignition electrodes should not be arranged too closely to one another and for this purpose a spacing of about 1 cm. with a

2

thickness of the ignition electrodes of some millimetres is sufficient. Preferably, use is made of at least four ignition electrodes operable in cyclic sequence.

The invention will now be explained more fully by reference to the accompanying diagrammatic drawing, given by way of example, showing an electric discharge tube 1 having a liquid cathode 2 and a liquid anode 3. Provided in the cathode are five capacitive ignition electrodes 4, each constituted by a molybdenum pin provided in the bottom of the tube and covered with glass having a low dielectric loss. Reference numeral 5 indicates an ignition-voltage source comprising a device for supplying the ignition pulses to the ignition electrodes 4 in cyclic sequence. The load on the tube is constituted by an inductor 6 and a capacitor 7, which jointly constitute a damped oscillatory circuit fed from a direct-voltage source 8.

What I claim is:

1. A vapor discharge device comprising an electric discharge tube having a liquid cathode and a plurality of spaced capacitative ignition electrodes, means to generate ignition pulses, and means to sequentially connect each of said ignition electrodes to said pulse generating means.
2. A device as claimed in claim 1 in which the spacing between adjacent ignition electrodes is greater than their thickness.
3. A device as claimed in claim 2 in which the tube has at least four ignition electrodes.
4. A device as claimed in claim 1 in which the ignition electrodes are operated in cyclic sequence.
